[57] **CLAIM**

The ornamental design for a staff for a pennant, as shown and described.

DESCRIPTION

FIG. 1 is a top, front perspective view of a staff for a pennant showing my new design;

FIG. 2 is an enlarged side elevational view thereof, the opposite side being a mirror image;

FIG. 3 is a top plan view thereof on an enlarged scale; and

FIG. 4 is a rear view thereof on an enlarged scale.
